Chas. Lynn Russell

UNITED STATES PATENT OFFICE.

ALBERT B. VIETH, SR., OF PHILADELPHIA, PENNSYLVANIA.

BOX OPENER.

Application filed June 15, 1922. Serial No. 568,443.

To all whom it may concern:

Be it known that I, ALBERT B. VIETH, Sr., a citizen of the United States, residing at Philadelphia, Pennsylvania, have invented 5 new and useful Improvements in Box Openers, of which the following is a specification.

The object of this invention is to provide an improved device for unseating and raising the covers of containers, as for instance, 10 metal boxes designed for containing pastes of various kinds.

In the drawings accompanying this specification one practicable embodiment of the invention is shown applied to a box by way 15 of illustration, in which drawings,

Figure 1 shows a sheet metal box equipped with my improved opening device, the box being closed.

Fig. 2 shows the box illustrated in Fig. 20 1 with the opener moved to its opening position and the cover moved slightly beyond the region of engagement therewith.

Fig. 3 is an enlarged horizontal section taken at about the center of the fastening device as seen in Fig. 1, and

Fig. 4 has an elevation on about the scale of Fig. 3.

Many of the existing forms of openers, particularly those used upon boxes for containing creams and pastes having a liquid constituent or a volatile ingredient, have been found objectionable owing to the fact that a hole necessarily had to be punched through the wall of the box to carry the 35 pivot pin of the lid raising lever. According to my invention, a fastening device in the form of a lever, 5, is shown carried wholly upon the outside of the body, 6, of a box adapted to engage the edge of the cover, or lid, 7, for unseating this. The lever, 5, is shown pivoted to a bridge, 8, which in turn is soldered or spot welded, or secured in some other suitable manner, to the body, 6, of the box. The center portion of the 45 bridge is shown raised sufficiently above the end portions to admit the head of the rivet, 9, between the bridge and the wall of the box.

I contemplate making the fastening device, comprising the lever riveted to the bridge, as an article of manufacture and supplying this to box manufacturers for their application, and also to supply the

boxes equipped with this device as the demands of the trade may require.

The lower edge of the side of the cover is preferably provided with an outwardly directed flange, 10, to afford a convenient shoulder or abutment for the engagement of the nose of the lever, irrespective of the angular position which the cover may assume relatively to the box. The side of the box is shown provided with a stiffening bead 11, which also serves to limit the downward movement of the cover. This bead is shown 60 interrupted at the region of application of the bridge, and for a sufficient distance each side thereof to permit the necessary rotation of the lever.

The rivet, 9, will preferably be sufficiently 70 tight to hold the lever somewhat flexed when in the Figure 1 position, so that it will remain in that position. When it is desired to open the box the lever is moved from the Figure 1 to the Figure 2 position, 75 which raises the cover from the box. The nose of the lever is preferably long enough to extend to the top of the rim of the box so that the cover will be pushed clear of it at the point of engagement.

Necessary changes of detail may be made within the terms of the claims without departing from the spirit of my invention.

I claim as my invention:

1. A box opener, comprising an arched bridge, an opening lever, and a rivet connecting the lever and bridge, the head of the rivet being located within the arch of the bridge, said bridge being adapted for application to the body of the box.

2. A box opener, comprising a sheet metal attaching member having flat extending ends for securement to the body of a box and an arch shaped central portion, and a cover engaging lever, the lever being riveted to the arch portion of the fastening member.

3. A box opener, comprising a securing bridge formed of sheet metal and having ends of considerable area for securement to the cover of a box, and an elevated substantially flat central portion, a curved lever, and a rivet passing through the lever and central portion of the bridge and holding the lever flexed when in alignment with the ends of the bridge.

4. The combination with a sheet metal box having a cover, the sides of the cover and body of the box having telescopic relation, of an opener comprising a securing bridge formed of sheet metal and having ends of considerable area secured to the side of the box, and an elevated central portion

between such ends, a lever for engaging the cover, and a rivet passing through the lever and the central portion of the bridge and ¹⁰ having its head located between the bridge and the side of the box.

ALBERT B. VIETH, SR.
